GEORGE W. JONES AND HARVEY D. ROBERSON, OF LEOMINSTER, MASSACHUSETTS,
ASSIGNEES TO WACHUSSETT SHIRT COMPANY, OF LEOMINSTER, MASSACHUSETTS,
A CORPORATION OF MASSACHUSETTS.

SOFT COLLAR.

Application filed March 2, 1928. Serial No. 258,586.

This invention relates to a soft collar of either the attached or detached style.

The principal objects of the invention are to provide a soft collar with means by which it will stay firmly in place and not sag down around the neck, without the use of starch or stiffening, and to avoid the thick hems heretofore necessary when a stiffening material has been employed and thus provide a collar of a neat and attractive appearance.

The collar is designed to have the same material outside as the shirt and present all the style and appearance of a laundered or stiff collar and yet retain the ease and comfort of a soft collar and avoid the bulkiness and thickness at the hems.

Other objects and advantages of the invention will appear hereinafter.

Reference is to be had to the accompanying drawings in which

Fig. 1 is a view of the inner side of one end of a collar with the lining broken away to show the interior construction;

Fig. 2 is a sectional perspective view on the line 2—2 of Fig. 1 and on enlarged scale, and

Fig. 3 is a similar view of the stiffening material of the collar.

It has been customary heretofore to make a soft collar with a multiply interwoven fabric inside, constituting a stiffening piece which is hemmed over at the top and bottom and forms a very bulky hem and unsightly appearance, particularly after it is ironed.

This invention is designed to avoid the use of an interwoven multiply stiffening material and particularly the hemming of such a fabric at the edge and the elimination of the bulky hem at the top and bottom. This invention can be used as a detached collar or as an attached one and the latter is shown in the drawings.

The collar is shown as comprising a neck band having an inner layer 10 and an outer layer 11 of self-material, that is, material of the same character as that of the shirt 12, which is to be sewed between the lower edges of the two layers 10 and 11. The outer layer 50 of self material 11 is reinforced by two layers 13 and 14 of stiffly woven single-ply webbing. The rear layer of this fabric is turned

over with the hem at the top as indicated at 15. At the bottom this layer comes within the hem 16 which is formed of the material 55 of the outer fabric 11. The inner layer 14 is not turned over at all either at the top or bottom. In this way it will be seen that the presence of a bulky hem is avoided. Of course, the two seams 17 and 18 forming the 60 hem are located longitudinally and pass through four layers at the bottom and five layers at the top.

The two layers of stiffening material 13 and 14 are sewed together by a series of rows 65 of stitches 19 which may be longitudinal, as indicated, but do not pass through the rear layer 11 or front layer 10. Therefore, these stitches are entirely concealed from view. The seams 17 and 18 which form the above 70 mentioned hems pass through the inner piece 10 and also the flap 20 of the collar, which is made in any of the usual ways, but which is secured in its place without any hem in its own material. The stitching 18 of course 75 stitches the neck band to the top of the shirt.

In this way a collar is produced having a stiff neck band which will stay in place like a starched collar and yet is comparatively soft and flexible. It holds the flap 20 80 in position just as if the whole of the collar were starched, yet the softness, which is desirable, is not lost and the whole collar has the feeling of a soft collar, although it stands up nearly as well as if it were starched all 85 over. There need be no starch in it, although a small amount of starch may be used as is the general practice in this type of collar.

Although we have illustrated and described only one form of the invention we are aware of the fact that modifications can be made therein by any person skilled in the art without departing from the scope of the invention as expressed in the claim. 90

Therefore, we do not wish to be limited in these respects but what we do claim is:—

As an article of manufacture, a collar comprising a flap, a neck band consisting of an inner fabric and an outer fabric, both of 100 the same material and both hemmed over at the top and bottom and secured together, the flap being secured between the tops of said inner and outer fabrics by a line of stitching,

two layers of single-ply stiffening material being located on the inner side of the back piece of the neck band, one of them extending to the hem only and the other being turned over at that end and under the outer piece to form the hem at the top, the two layers of interlining being stitched together

by parallel rows of stitching, the outer layer of material entirely concealing said parallel rows of stitches.

In testimony whereof we have hereunto affixed our signatures.

GEORGE W. JONES.

HARVEY D. ROBERSON.
